DESIGN FOR AN EMBROIDERED FABRIC

Morris Leff, Brooklyn, N. Y.

Application April 11, 1938, Serial No. 76,426

Term of patent 3½ years

To all whom it may concern:

Be it known that I, Morris Leff, a citizen of the United States of America, residing in New York city, in the Borough of Brooklyn, county of Kings, and State of New York, have invented a new, original, and ornamental Design for an Embroidered Fabric, of which the following is a specification, reference being had to the accompanying drawing, forming part thereof, wherein,

The figure is a plan view of a piece of embroidered fabric, showing my new design between the selvage edges.

I claim:

The ornamental design for an embroidered fabric, substantially as shown and described.

MORRIS LEFF.
